UNITED STATES PATENT OFFICE.

ROBERT JOHN SHIELDS, OF HOBGOOD, NORTH CAROLINA.

TORPEDO-GUARD FOR SHIPS.

1,271,090.

Specification of Letters Patent.

Patented July 2, 1918.

Application filed April 13, 1918. Serial No. 228,397.

To all whom it may concern:

Be it known that I, ROBERT JOHN SHIELDS, a citizen of the United States, residing at Hobgood, in the county of Halifax and 5 State of North Carolina, have invented certain new and useful Improvements in Torpedo-Guards for Ships; and I do hereby declare the following to be a full, clear, and exact description of the invention, such as 10 will enable others skilled in the art to which it appertains to make and use the same.

The object of my invention is to provide a novel form of torpedo-guard for ships, which shall be of extreme simplicity in construction and of great efficiency in use.

A further object of my invention is to provide a construction of torpedo-guard which, in addition to its primary function of guarding ships from torpedo attack, will 20 be capable of performing the function of assisting in propelling the vessel.

Subsidiary objects, relating to specific improvements, will appear as the specification proceeds and the nature of the invention 25 more fully appears.

The invention is graphically illustrated in the accompanying drawing in which like reference - characters denote corresponding parts throughout the several views, which 30 latter may be briefly described as follows:

Figure 1 is a fragmentary sectional view of the side of a ship, showing my torpedo-guard and operating means therefor in operative relation thereto, the bearings being 35 shown in section;

Fig. 2 is a sectional view along the line 2—2, Fig. 1, looking in the direction of the arrows; and

Fig. 3 is a similar view showing a slightly 40 modified form of supporting means for torpedo-guards.

Referring, now, in detail to the drawing and, first, to Figs. 1 and 2 thereof:

The basic idea of my invention is the utilization of torpedo-guards of a shape resembling a screw propeller, or Archimedean screw, *i. e.*, a member comprising a shaft 1 carrying a sinuous or undulating or helical vane 2 extending longitudinally thereof.

50 My invention contemplates employing either one or two, or a plurality, of such guards, at each side of the vessel. As an illustration, I have shown in the drawing two of such guards disposed in axial alinement, or 55 end to end, though it is obvious, of course, that, instead of two guards disposed in this

relation, one guard of a length equal to the two shown, or of the desired length, may be employed. It is desirable to use at least two guards disposed end to end, at each side 60 of the vessel, since, if one is injured, it may be removed and a new one installed, without disturbing the other.

Suitable means for rotatably supporting the guards are necessarily provided, and in 65 the drawing I have shown my preferred form thereof, which I will now describe. At adjacent ends, the guard-shafts 1, 1 are rotatably supported in a bearing 3, common to both shafts, carried by a bracket 4 suitably secured to the exterior face of the side 70 5 of the vessel. Each shaft 1, at its opposite end, is rotatably supported in a bearing 6, forming part of a water-tight and dust-proof box 7 bolted, as at 8, or otherwise suitably secured, to a bracket 9 attached to the side 5 of the ship. Each shaft 1 carries, fast thereon, collars, 10, 10 abutting the outer ends of the bearings 3 and 6 and maintaining the shaft against movement in the direction of the length thereof.

Each shaft 1 carries, at its outer end, a beveled gear 11 meshing with a similar gear 12 on a counter-shaft 13 supported in bearings in said bracket 9 and also in a tubular bearing 14. The bearing 14 projects through the side 5 of the ship, and is preferably provided with a flange 15 bearing against the exterior face of the side 5 of the ship, as shown. Threaded into the end of said 90 bearing 14 is a plug 15 compressing the packing in said bearing around the shaft 13.

That end of said shaft 13 which is inside the ship carries a bevel gear 16 meshing with a larger or multiplying gear 17 carried on the end of a shaft 18, rotatably supported in bearings 19, 19 in a casting or bracket 20 secured to the inner face of the side 5 of the ship. The opposite end of the shaft 18 carries a gear 21, which may be driven from any suitable source of power.

It will be understood that there may be a plurality of series of these guards, one series placed beneath the other and extending from approximately the water line of the vessel to the desired depth beneath the water line; though the vane 2 of a single line of guards may be of dimensions sufficient to afford the desired protection.

110 In operation, it will be obvious that the rotating torpedo-guards will intercept a

torpedo fired at the ship, and the helical vanes will tend to deflect and throw the torpedo away from the ship.

Referring, now, to the disclosure of Fig. 3: the only difference between this form and the form shown in the preceding figures is in the construction of the bracket 9^a. This bracket is adapted to be attached to the side 5^a of the ship in a position inclined with reference thereto, and, for this purpose, that end of the tubular bracket which is adapted to abut the side of the ship is sheared off at an angle to the diametric line of said bracket, as clearly shown. Projecting axially through said tubular bracket 9^a is the shaft 13^a carrying, at one end, the pinion 16^a meshing with the driving gear 17^a on the shaft 18^a carried by the bracket 20^a. The shaft 13^a rotates in a bearing 14^a provided with a screw-follower 15^a to compress the packing therein. This tubular bearing 14^a is provided with a flange 15^b bearing against the exterior face of the side 5^a of the ship. The lower end of the shaft 13^a carries a beveled gear 12^a meshing with the beveled gear 11^a on the shaft 1^a carrying the torpedo guard 2^a (which is the same as the torpedo-guard of the preceding figures). Secured to the lower end of the bracket 9^a, as by fastening means 8^a, is the box 7^a inclosing the gears 11^a and 12^a.

Having thus fully described my invention, what I claim as new and desire to secure by Letters Patent is:

35 1. A torpedo guard for vessels comprising a shaft rotatably supported adjacent the side of the vessel, and provided with a helical vane extending longitudinally thereof, said shaft being journaled in bearings projecting from the side of the vessel and said vane being slightly removed from said side and its peripheral portion extending slightly above the water line.

45 2. A torpedo guard for vessels comprising two rotatable shafts disposed end to end, and each provided with a helical vane extending longitudinally thereof, and supporting means, common to both shafts, for rotatably supporting adjacent ends thereof.

50 3. A torpedo guard for vessels comprising two rotatable shafts disposed end to end,

and each provided with a helical vane extending beside the vessel slightly removed therefrom and having its peripheral portion above the water line and the major part 55 thereof submerged longitudinally thereof, supporting means, common to both shafts, for rotatably supporting the adjacent ends thereof, a gear carried at the opposite end of each shaft, a water-tight box inclosing each of said gears, and means for driving said gears from the inside of the ship.

4. A torpedo guard for vessels comprising two rotatable shafts disposed end to end, and each provided with a helical vane 65 extending beside the vessel slightly removed therefrom and having its peripheral portion above the water line and the major part thereof submerged longitudinally thereof, supporting means, common to both shafts, 70 for rotatably supporting the adjacent ends thereof, a gear carried at the opposite end of each shaft, a water-tight box inclosing each of said gears, a bracket carrying each box and adapted to be attached to the side of 75 the ship, and means for driving said gears from the inside of the ship.

5. A torpedo guard for vessels comprising two rotatable shafts disposed end to end, 80 and each provided with a helical vane extending beside the vessel slightly removed therefrom and having its peripheral portion above the water line and the major part thereof submerged longitudinally thereof, supporting means, common to both shafts, 85 for rotatably supporting the adjacent ends thereof, a gear carried at the opposite end of each shaft, a water-tight box inclosing each of said gears, a hollow, water-tight bracket detachably connected with each of 90 said boxes, and means for driving said gears from the inside of the ship, including gears meshing with said first-mentioned gears and carried at the ends of shafts projecting through said brackets.

In testimony whereof I affix my signature in the presence of two witnesses.

ROBERT JOHN SHIELDS.
